UNITED STATES PATENT OFFICE.

GEORGE W. WILMOT AND FRANCIS H. BLATCH, OF HAZLETON, PENNSYLVANIA,
ASSIGNORS TO WILMOT ENGINEERING COMPANY, OF HAZLETON, PENNSYLVANIA, A CORPORATION OF PENNSYLVANIA.

COAL JIG.

Application filed September 26, 1922. Serial No. 590,593.

To all whom it may concern:

Be it known that we, GEORGE W. WILMOT and FRANCIS H. BLATCH, citizens of the United States, and residents of Hazleton, in the county of Luzerne and State of Pennsylvania, have invented an Improvement in Coal Jigs, of which the following is a specification.

Our invention relates to apparatus designed primarily for washing coal but which may be employed also for washing ores of various kinds.

The general object of the invention is to provide an apparatus embodying novel means by which it is particularly adapted for use in the washing or jiggling of the smaller commercial sizes of coal, and a still further object is to provide a novel construction of means whereby the apparatus shall be, as far as is possible practical, self-cleaning.

A further object of the invention is to provide means whereby the direction of the flow of water upwardly through the jig pan may be controlled to thereby render the operation of the apparatus more efficient than heretofore has been the case.

To these and other ends our invention comprehends the construction and arrangement of parts as hereinafter described in detail, particularly pointed out in the claims, and as illustrated in the drawings in which we have illustrated one form of embodiment of jig structure embodying our invention. However, it will be understood that our invention is susceptible of embodiment in other forms of construction than that shown and that changes in the details thereof may be made within the scope of the claims without departing from the said invention.

In the drawings:

Fig. 1 is a central vertical sectional view of a portion of a coal jig apparatus embodying our invention;

Fig. 2 is a horizontal sectional view of a portion of the apparatus showing a portion of the valve structure in top plan;

Fig. 3 is a transverse sectional view taken on the line 3-3 of Fig. 2;

Fig. 4 is a transverse vertical sectional view taken on the line 4-4 of Fig. 1;

Fig. 5 is a view taken on the line 5-5 of Fig. 1; and

Fig. 6 is a view similar to that shown in Fig. 3 showing a slightly modified means for retaining the tubular valves in co-operative relation with respect to the seats therefor.

Referring to the drawings: 1 designates a tank for holding water having a valve controlled outlet at 2 of known construction and operating in known manner. The coal or other material to be washed is introduced into the jig pan 3 at the point 4 and its passage from its point of introduction toward the rear or discharge end of the jig pan is controlled to a greater or less extent by the adjustable plate 5. The bottom 6 of the jig pan is perforated in known manner. The jig pan is supported upon the sides of the tank 1 in known manner.

The tank 1 is filled with water to such an extent that the top level thereof occupies a plane a short distance below the upper edges of the opposite sides of the jig pan 3, and in order that the same may be agitated and a current caused to flow upwardly through the jig pan and over the upper edge of the discharge end thereof a plunger is provided having a valve structure which operates to cause upward flow of the water through the said jig pan. The said plunger comprises a frame designated as a whole by the reference numeral 8 which frame is provided with bearing portions 9 which are adapted to bear against the inside surfaces of the walls of the casing 10 within which the plunger is situated and within which it operates. The said casing is secured to and depends from the bottom of the jig pan 3. The rear end portion of the plunger is situated underneath the rear or discharge end portion of the jig pan while the opposite or front end portion or side of the said plunger terminates a distance inwardly of the front end portion of the said jig pan. In order, however, that the water may be permitted to flow through the perforations in the bottom of the jig pan at the front end portion of the latter underneath the point of delivery thereto of the coal or ore to be washed we have extended the front wall of the casing 10 forwardly as indicated at 11.

The wall 11 is continued by means of a hinged gate or door 12 which is connected at its opposite ends as indicated at 13 to the lower end of angular links 14 connected

at their upper ends by means of a bolt 15 to the inner end of a lever 16 pivoted intermediate its ends at 17 upon a standard or bracket 18 which projects upwardly from 5 a cross-bar 19 supported at its opposite ends upon the top sills of the tank structure. In order that the lever 16 may be held in position as shown in Fig. 1 with the door or gate 12 closed we have provided the upright 10 rod or bar 20 which terminates at its upper end in a hook 21 with which the outer end of the said lever 16 is adapted to be engaged and disengaged for the purpose of holding the said gate in closed position and for the 15 purpose of permitting the same to open.

In the construction as shown the plunger comprises a couple of members 25 and 26 which are adapted to be placed in edge to edge contact relation with respect to each 20 other, as shown, and the opposite ends of which are adapted to be secured to the frame structure 8 of the plunger. These members 25 and 26 are provided with parallel slots 29, as indicated, and the bars 30 25 separating the said slots have tapering upper and lower edges, as indicated at 31 and 32, so that in cross-section the said bars (except those at the opposite sides of each of the members 25 and 26) may be described 30 generally as being of diamond-shape. The valves 33 for controlling the passage of water through the openings provided by the slots 29 are tubular and are adapted to be seated upon or against the adjacent opposing surfaces 31 of adjacent bars upon 35 opposite sides of the respective slots. It will be noted, as already indicated, that the bars 30 at the opposite sides of the members 25 and 26 are triangular in cross-section 40 and not quadrilateral as is the case with the intermediate bars 30; and also that the said bars 30 at the inner edges or sides of the members 25 and 26 which are in contact with each other combine to produce 45 a divisional bar which in cross-section is of diamond-shape, as shown in Fig. 3.

The opposite ends of the tubes 33 may be closed and in order that the weight of the said tubes may be varied material, such 50 as liquid or a granulated solid material, may be inserted into the said tubes. By varying the weights of the tubes their sensitivity to the action of the water thereon during the reciprocating movements of the plunger, to be hereinafter described, may be varied and controlled. For the purpose of retaining the tubes 33 in co-operative relation to their respective seats we have provided retaining bars 38 which extend across the members 25 and 26 and are secured to projections 40 at the outer edges thereof. For the purpose of protecting the valve structure just described against foreign matter and for preventing the latter 55 from accumulating upon the said valve

structure we have provided a shield or protector situated a distance below the said valve structure which shield or protector comprises a plate 45 which is extended downwardly, as indicated in Fig. 3, and 60 which is provided with perforations as shown at 46. These perforations are of the size to permit the free passage of water to the valve structure, but are sufficiently small to prevent the passage of foreign matter to the said valve structure of a character to interfere with the operation thereof. The said shield or protecting plate 45 is secured by means of bolts 47 to the outer lower edges of the frame 8 of the plunger 65 previously referred to. The same bolts operate also to secure to the lower sides of the said frame the brackets 50 at opposite sides of the frame structure to which brackets the lower ends of the connecting 70 bars 51 are secured. The upper ends of the said bars are suspended from eccentrics 53 which are mounted upon a shaft 54 supported in bearings 55 upon the opposite sides of the tank frame structure. This 75 shaft is driven in known manner. Rotation of the said shaft effects reciprocation of the connecting bars 51 which in turn effects reciprocation of the plunger within the casting 10.

In the construction as shown in Fig. 6 of the drawings the retaining bar 38' is provided with depending V-shape projections 58 which are situated directly above the bars 30 intermediate the tubular valves 33. 100

Upon reciprocation of the plunger the valves 33 are moved up and down to open and close the passageways between the bars 30. Upon descending movement of the plunger the water pressing upwardly 105 against the valves 33 causes the same to open whereupon streams of water flow upwardly through the openings 29 between the said bars 30. Upon lifting movement of the plunger the valves 33 close so as to 110 force the water which previously flowed upwardly through the openings 29 upwardly through the perforations in the bottom 6 of the jig pan 3 and thence on upwardly so as to cause an overflow of the water at the 115 discharge end of the jig pan to effect forward movement of the coal and the slate and other relatively heavy material which may have been separated out from the coal. The coal being the lighter is discharged 120 from an upper passageway on to the endless carrier 60 while the slate and other material being heavier is discharged from a lower outlet on to the endless carrier 61. These carriers convey the coal from the jig 125 tank in known manner.

The purpose of providing the bars 30 with tapering surfaces 31 and 32 is that the valve structure shall, as far as possible, be self-cleaning. By the employment of bars of the 130

character illustrated as valve seats it will be apparent that the tendency will be to prevent the lodgment of any foreign substance upon the outer surfaces thereof which would interfere with the proper operation of the valves 33. For this reason we have referred to the valve structure as being a self-cleaning or self-clearing structure. This provision taken in connection with the shield or 5 protector 45 is sufficient to keep the valve structure in a relatively clean condition whereby the efficiency of the apparatus is substantially enhanced. Also by reason of the presence of the gate or door 12 the center 10 of the casing 10 and the lower side of the bottom 6 of the jig pan may be readily cleansed. By opening the said door or gate the water may be caused to flow rapidly downwardly through the opening thus produced so as to sweep or wash from the inside 15 surfaces of the said casing and from the bottom surface of the bottom 6 any material which may have collected on such surfaces and which might interfere 20 with the efficient operation of the apparatus.

In order to control to a greater or less degree the flow of water through the casing 10 toward that portion of the bottom 6 of the jig pan directly underneath the point of delivery to the jig pan of the coal or other material to be washed we have provided the adjustable plate 65 which extends transversely 30 of the apparatus and which is situated at a point above the forward edge portion of the plunger previously described. The plate 65 is pivotally supported at its opposite ends in the sides of the casing and for the purpose of adjusting the same is provided with an arm 66 which extends laterally therefrom and to the outer end of which the inner end 35 of an operating rod or bar 67 is connected. The outer end of said bar is situated in a position to be readily accessible for operation. Adjacent its outer end the operating bar 67 is provided with notches 70 which are 40 adapted to engage the upper edge of a catch plate 71 supported upon a top sill of the tank frame structure. By adjusting the plate 65 to different positions the amount of water permitted to flow toward the left, having reference to Fig. 1 of the drawings, from 45 the plunger so as to pass through perforations in the front portion of the bottom 6 of the jig pan may be varied and controlled. In 50 like manner and for the purpose of being able to increase the amount of water caused to flow toward the right from the said plunger and upwardly through the perforations of the bottom of the jig pan near the discharge end thereof, particularly at the point where the slate is discharged, we have provided an adjustable transversely extending plate 73 pivoted at its opposite ends upon 55 the casing 10 and provided adjacent one end with an arm 74 to the upper outer end of

which the inner end of an operating rod or bar 75 is secured. The outer upper end of the said rod or bar is situated in a position to be easily accessible for operation, and the lower side of the upper edge portion thereof is 60 provided with notches 76 at intervals which are adapted to engage with the upper edge of a catch plate 77 which is secured to one of the top side sills of the tank frame structure. By operating the rod or bar 75 the 65 plate 73 may be angularly adjusted about its axis so as to control the direction of the flow of a portion of the water which passes through the valve structure of the said plunger. When the plate 73 is in the position as 70 shown a considerable portion of the water, almost half, which passes upwardly through the said plunger will be caused to flow toward the right, having reference to Fig. 1 of the drawings, and to enter the jig tank 3 at 75 a point adjacent the point of discharge of the slate or other relatively heavy material therefrom. As will be apparent the plate 73 may be adjusted so as to occupy a position parallel with the plane of the plunger 80 and that when in such position the water flowing upwardly through the plunger opposite the said plate will be deflected equally in opposite directions, toward the front and the rear of the jig pan. If the plate be 85 adjusted so that it is inclined in a direction opposite to that in which it is shown in Fig. 1 of the drawings it will be apparent that the water flowing through the plunger and which strikes against the said plate would 90 be deflected toward the left instead of toward the right, as is the case at present.

It will be seen that we have provided an apparatus of unitary construction and design which is provided with means whereby the valves of the plunger for effecting the flow of water through the jig pan are self-cleaning, and also with means whereby the said valve structure is protected. It will 100 also be seen that we have provided means whereby the direction of the flow of water from the passageways through the reciprocating plunger may be controlled and varied as may be desired and also that we have provided means whereby the bottom surface of 105 the bottom of the jig pan and the surface of the inclosing casing which depends from the bottom of the jig pan may be readily and thoroughly closed.

Having thus described our invention what 110 we claim and desire to secure by Letters Patent is:

1. A coal or ore washing machine comprising a reciprocating plunger for causing 115 a flow of water upwardly through the coal or ore to be washed, the said plunger including a plurality of bars arranged in spaced parallel relation to each other, the upper and lower edges of which bars are 120 wedge-shaped, and tubular valves situated 125

41
between the opposing tapered sides of the upper edges of adjacent bars, substantially as described.

2. A coal or ore washing machine comprising a reciprocating plunger for causing a flow of water upwardly through the coal or ore to be washed, the said plunger including a plurality of spaced parallel bars, the spaces between the said bars constituting 10 openings through which the water flows upwardly through the said plunger, the upper portions of said bars being tapered so that in cross-section the upper edge is of wedge-shape, and tubular valves situated between the adjacent sides of the wedge-shape 15 portions of adjacent bars, substantially as described.

3. In a coal jig, the combination of a jig pan, a casing projecting downwardly from 20 the said jig pan and forming a chamber underneath the bottom thereof, a plunger situated within the said casing, means for effecting reciprocation of said plunger, a valve structure carried by said plunger for 25 permitting an upward flow of water therethrough and preventing a downward flow, and means intermediate the said plunger and the bottom of the said jig pan whereby the direction of the flow of portions of the water 30 after it passes through the said plunger may be directed and controlled.

4. In a coal jig, the combination of a jig pan having a perforated bottom, a casing supported underneath the said jig pan and 35 providing a chamber underneath the bottom thereof, a plunger situated within the said casing, means for causing reciprocation of 40 said plunger which plunger is provided with means for causing a flow of water upwardly through the said jig pan, adjustable plates situated intermediate the plunger and the bottom of the said jig pan adjacent the front and rear end portions of the said plunger, and means for adjusting the said plates 45 whereby the direction of the flow of portions of the water which may flow upwardly through the said plunger may be controlled.

5. In a coal jig, the combination of a stationary jig pan having a perforated bottom, 50 a casing depending from the said jig pan having vertical side and rear walls and the lower portion of the front wall of which is vertical while the upper portion thereof is inclined toward the front of the machine and 55 comprises a hinged section constituting a gate, means whereby the said gate may be opened and closed, and means for effecting reciprocation of the said plunger to effect 60 flow of water upwardly through said jig pan and forwardly and out of the space between the said plunger and the said jig pan through the said gate controlled opening when the latter is opened, substantially as described.

6. In a coal jig, the combination of a stationary jig pan having a perforated bottom, a casing depending from the said jig pan and providing a chamber underneath the bottom thereof, the side and rear walls of 65 said casing being vertical and the front wall thereof including a vertical and forwardly inclined portion the latter having a hinged portion which constitutes a gate for opening and closing an opening leading from the 70 said chamber, means for opening and closing the said gate, a plunger situated in the lower portion of said casing the said plunger including a valve structure which is adapted to operate to cause an upward flow of water 75 through the plunger structure, and adjustable means within the space between the plunger and the bottom of the said jig pan whereby the direction of the flow of water after it passes through the valve structure of 80 the said plunger and enters the said space 85 may be directed and controlled.

7. In a coal jig, the combination of a jig pan, a casing situated underneath the same and providing a chamber underneath the bottom of said jig pan, a plunger situated 90 and operating within the lower portion of the said casing, said plunger including a valve structure for controlling the flow of water upwardly therethrough, plates pivotally supported within the space between the 95 said plunger and the bottom of the said jig pan, the said plates extending transversely and parallel with the bottom of said jig pan, and manually operable means for effecting 100 adjustment of the said plate, substantially as described.

8. In a coal jig, the combination of a jig pan, a reciprocating plunger having a valve structure which is adapted to cause a flow 105 of water through the said jig pan, and a shield having connection with the said plunger and situated underneath the said valve structure for protecting and shielding the latter against foreign matter to thereby prevent interference with or interruption of 110 the efficient operation of the said valve structure.

9. In a coal jig, the combination of a jig pan, a plunger having a valve structure 115 which is adapted to permit a flow of water upwardly through the said plunger and to cause forward flowing movement thereof through the said jig pan, means for effecting reciprocation of the said plunger, and a screen plate carried by the said plunger and situated underneath the said valve structure.

In testimony that we claim the foregoing as our invention we have hereunto signed our names this 22nd day of September, A. D., 1922.

GEORGE W. WILMOT.
FRANCIS H. BLATCH.
